UNITED STATES PATENT OFFICE.

GEORGE D. SNELL, OF DENVER, COLORADO.

ASH-PIT.

SPECIFICATION forming part of Letters Patent No. 417,398, dated December 17, 1889.

Application filed February 19, 1889. Serial No. 300,454. (No model.)

To all whom it may concern:

Be it known that I, GEORGE D. SNELL, of Denver, in the county of Arapahoe and State of Colorado, have invented a certain new and 5 useful Improvement in Ash-Pits, of which the following is a specification.

My invention relates to improvements in ash-pits, and has for its object the provision of a portable ash-pit which will prevent the 10 ashes being scattered by the wind, and will be cheap and simple in its construction.

The invention consists in certain novel features hereinafter described and claimed.

The accompanying drawings form a part of 15 this specification, and represent what I consider the best means of carrying out the invention.

Figure 1 is a side elevation of my improved ash-pit. Fig. 2 is a vertical longitudinal section on the same on the line $x x$ in Fig. 1. Fig. 3 is a plan view thereof, and Fig. 4 is a horizontal section on the line $y y$ of Fig. 2.

Similar letters of reference indicate corresponding parts in all the figures where they 25 occur.

A designates the body of the ash-pit, which is constructed of concrete or some similar composition, and is made in two sections B C, as shown, the upper section or member 30 resting upon the lower member and the edges of the two members overlapping. The lower member is provided at or near its lower edge with an opening D, through which the ashes may be removed. Around the edge of this 35 opening I arrange a metallic facing E, the front portion of which is bent over to form flanges F, bearing against the front of the body. The edges of these flanges are provided with vertical grooves G, and these 40 grooves are engaged by internal ribs H on a sliding door I, adapted to close the opening D, as will be readily understood.

On the upper end of the upper member of the body I place the lid P, covering the opening J, through which the ashes are passed 45 into the pit. This opening J is provided with a metallic facing K, similar to the facing E, and is closed by a cover L. The body may, if so desired, be placed on a base M of concrete; but this base is not essential. 50

From the foregoing description, taken in connection with the accompanying drawings, it will be seen that I have provided a very cheap and simple ash-pit, which can be readily taken apart for storage and transportation, and can be easily put together by unskilled persons. The device, being made of concrete, as shown and described, has few joints, and those few are all closed, so that it is impossible for the wind to scatter the 60 ashes.

My device is cheap, simple, and durable, and its advantages are thought to be obvious.

I claim as my invention—

1. An ash-pit made of concrete in sections 65 matched together, in combination with the lid P, having an aperture J and a removable cover for the latter, and with an aperture D in the side at the bottom, and a cover therefor, adapted to serve as herein specified. 70

2. The combination of the ash-pit having an opening in its lower portion, the metallic facing in said opening having grooved edges, and the sliding door having internal ribs engaging said grooved edges, as set forth. 75

In testimony whereof I have hereunto set my hand, at Denver, Colorado, this 12th day of February, 1889, in the presence of two subscribing witnesses.

GEORGE D. SNELL.
